UNITED STATES PATENT OFFICE.

CHARLES O. YOUNG, OF PITTSBURGH, PENNSYLVANIA, ASSIGNOR TO CARBIDE AND CARBON CHEMICALS CORPORATION, A CORPORATION OF NEW YORK.

PROCESS OF PRODUCING OXALIC ACID.

No Drawing.

Application filed April 5, 1920. Serial No. 371,536.

To all whom it may concern:

Be it known that I, CHARLES O. YOUNG, a citizen of the United States, residing at Pittsburgh, in the county of Allegheny and State of Pennsylvania, have invented certain new and useful Improvements in Processes of Producing Oxalic Acid, of which the following is a specification.

This invention is a novel process whereby 10 oxalic acid may be prepared, economically and with excellent yields, from carbohydrates or other appropriate oxidizable substances such as ethylene glycol. The process is not limited to the specific operating 15 details given below by way of example, although the conditions described are those which have been found most advantageous from the point of view of high yields, quality of product, and optimum results in general.

It has long been known that oxalic acid can be prepared from carbohydrates by oxidation with nitric acid. A large excess of nitric acid over the theoretical proportion 20 is however required, and a considerable part of the oxidizing power of the nitric acid is lost by the formation and evolution of nitrogen tetroxid according to the equation:

As indicated by the above equation 4 moles of nitric acid yield only one mole of available oxygen.

Similarly, ethylene glycol may be oxidized to oxalic acid by means of nitric acid, but such process is not efficient, owing to the loss of nitrogen tetroxid, and to the fact that the progressive dilution of the nitric acid prevents the reaction from proceeding to completion. For the above reasons the yields are low and the costs prohibitive.

In order to render possible the re-use of the dilute nitric acid solution which remains 45 after the concentration of acid has fallen below the point necessary for the oxidation of carbohydrates, it has been proposed to introduce gaseous or liquid nitrogen tetroxid into such solution to restore the initial nitric acid concentration; the nitrogen tetroxid for this purpose being obtained 50 from any suitable source, including the nitrous gases arising from the reaction itself. Such procedure, however, involves the isolation of nitrogen tetroxid from gaseous

mixtures by liquefaction processes, or otherwise, and is therefore both expensive and cumbersome.

I have discovered that oxidations of this type may be easily and economically effected, with excellent yields, by circulating through a closed system including an aqueous solution of the substance to be oxidized, a gas-mixture consisting essentially of nitrogen oxids and pure (substantially undiluted) oxygen. The process as applied for example to the preparation of oxalic acid from glycol may be regarded as taking place in three steps or operating stages, to wit:—

1. Absorption of N_2O_4 by the water of the 70 solution with formation of certain amounts of nitric acid;

2. Oxidation of glycol by the nitric acid thus formed, with evolution of more nitrogen tetroxid and lower oxids of nitrogen; 75

3. Oxidation of such lower oxids of nitrogen by the oxygen, together with a sufficient supply of undiluted oxygen from outside sources to regenerate the original mixture.

It will be observed therefore that the 80 process involves no necessary or theoretical loss of nitrogen compounds; nor does it involve any separation or isolation of nitrogen compounds from a complex gas-mixture.

Oxygen alone is consumed in the regular 85 operation of the process, so that for practical purposes it may be considered that the oxidation is performed by oxygen, the nitrogen compounds acting as carriers. Air or other form of dilute oxygen is of course 90 not equivalent to substantially pure oxygen for this purpose, since it is only by the use of substantially undiluted oxygen that the volume of gases in cyclic flow may be maintained approximately constant, or the increase in volume due to inert gases be maintained within reasonable and commercial 95 limits.

In practice the operation may for example be carried out as follows:—

An aqueous solution containing 40-50% of ethylene glycol is introduced into a tower or other appropriate form of reaction chamber of stoneware or other resistant material, and is maintained at about 60-80° C. A 105 strong stream of mixed gases $\text{N}_2\text{O}_4 + \text{O}_2$, is bubbled through the glycol solution, the excess gases being collected at the top of the tower and returned by means of a pump to pass again in contact with the solution in 110

- continuous cyclical flow. As the reaction proceeds the gas volume tends to diminish through absorption of oxygen, and means are accordingly provided for introducing 5 oxygen into the system to replenish that absorbed by the reaction and to maintain at all times oxygen in excess of the reaction requirements. After the operation is continued for some 6-7 hours, more or less, de- 10 pending on the rate of addition of the gases, the solution is withdrawn and permitted to cool. The oxalic acid crystallizes out, is filtered off, and the mother liquor containing unoxidized glycol and dissolved oxalic acid 15 is returned to the tower together with a new charge of glycol solution. The operation is then repeated.
- Inasmuch as there is always some tendency to the building up within the system 20 of inert gases, such as nitrogen, air, carbon dioxid, etc., it is necessary to provide an outlet for occasionally purging the system while maintaining a substantially constant average gas volume. These waste gases may 25 be passed through an alkaline solution whereby the nitrogen oxids are caught and subsequently recovered as alkali nitrate or nitrite. In this way loss of the valuable nitrogen oxids is minimized.
- 30 The initial supply of higher nitrogen oxids may be produced by any method desired, as for example from sodium nitrate by the action of sulfuric acid, or even by the addition of concentrated nitric acid to 35 the original glycol solution. This latter procedure illustrates the advantage of the present process as compared with the older processes of oxidizing by means of nitric acid, for a much smaller quantity of nitric acid is 40 adequate for charging the present system. The use of catalysts capable of accelerating

the reaction is of course not excluded, but is not regarded as essential inasmuch as very satisfactory yields may be obtained without the presence of any catalyst. In this con- 45 nection it may be remarked that the presence of small proportions of vanadium oxid dissolved in nitric acid acts to retard the oxidation of glycol under the conditions herein described. 50

The reaction when carried out as above described affords yields considerably in excess of those obtainable by the ordinary methods of nitric acid oxidation, 70-80% of the theoretical yield of oxalic acid being 55 readily recoverable. The reaction proceeds satisfactorily at pressures just sufficient to maintain the gas flow through the system. However higher or lower pressures may be used as may be desired. 60

I claim:-

1. Process of preparing oxalic acid from water-soluble substances capable of yielding the same by oxidation, comprising circulating a gaseous mixture of nitrogen oxids and oxygen in contact with an aqueous solution of such substance in a closed circulating system, and supplying substantially undiluted oxygen in proportion to satisfy the reaction requirements. 70

2. Process of preparing oxalic acid from ethylene glycol, comprising circulating a gaseous mixture of nitrogen oxids and oxygen in contact with an aqueous solution of glycol in a closed circulating system, and supplying substantially pure oxygen in proportion to satisfy the reaction requirements. 75

In testimony whereof, I affix my signature.

CHARLES O. YOUNG.
